United States Patent Office

Des. 216,239
Patented Dec. 2, 1969

216,239

TEXTILE FABRIC

Leonard C. Clementi, Huntington, N.Y., assignor to Cannon Mills Company, Kannapolis, N.C., a corporation of North Carolina

Filed Nov. 25, 1968, Ser. No. 14,659

Term of patent 14 years

Int. Cl. D5—02

U.S. Cl. D92—1

Fig-1

I claim:

The ornamental design for a textile fabric, substantially as shown and described.
